Primary Examiner — Katherine A Holbrow*Assistant Examiner* — Riya Salil Kamat(74) *Attorney, Agent, or Firm* — Jonathan E. Grant; Grant Patent Service(57) **CLAIM**

The ornamental design for a toy magnetic wheel track, as shown and described.

DESCRIPTION

FIG. 1 is a front perspective view of a toy magnetic wheel track, where the rear perspective view is a mirror image thereof;

FIG. 2 is a front view thereof;

FIG. 3 is a rear view thereof;

FIG. 4 is a first side-view thereof;

FIG. 5 is a second side-view thereof;

FIG. 6 is a top view thereof; and,

FIG. 7 is a bottom view thereof.

The broken lines illustrate portions of the toy magnetic wheel track that form no part of the claimed design.
